(57) **CLAIM**

The ornamental design for a guitar pick, as shown and described.

DESCRIPTION

FIG. 1 is a perspective top left side view of the guitar pick of the present invention showing my new design;

FIG. 2 is a perspective top right side view thereof;

FIG. 3 is a perspective bottom back end view thereof;

FIG. 4 is a perspective bottom left side view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a back end view thereof.

Lines and shading appearing on the surface of the guitar pick in the various variations are provided to clearly show the character and three-dimensional aspects of the design.
